UNITED STATES PATENT OFFICE.

ALEXANDER E. BROWN, OF CLEVELAND, OHIO, ASSIGNOR TO THE BROWN
HOISTING MACHINERY COMPANY, OF CLEVELAND, OHIO.

SUPPORT FOR CROWN OR ANTENNA WIRES FOR ELECTRIC MASTS.

No. 857,152.

Specification of Letters Patent.

Patented June 18, 1907.

Application filed January 18, 1907. Serial No. 352,971.

To all whom it may concern:

Be it known that I, ALEXANDER E. BROWN, a citizen of the United States, residing at Cleveland, in the county of Cuyahoga and State of Ohio, have invented a new and useful Support for Crown or Antenna Wires for Electric Masts; and I hereby declare the following to be a full, clear, and exact description of the same, reference being had to the drawings accompanying and making a part of this application, wherein similar parts in each case are denoted by the same referential letters.

As indicated above, my invention relates, generally, to the apparatus employed in space, or wireless telegraphing wherein electrically produced vibrations are to be radiated, or received at an elevated point, above the operative station, but, more particularly, to that class of such apparatus, in which the elevating medium or member, is a mast or single tubular shaft or staff (as contra-distinguished from a tower or raised platform) to which the requisite crown or antennæ wires are attached at its top. As will be understood, a mast of the latter kind, is in most cases an insulated cylindrical metallic column or shaft, that carries, at its top, the necessary crown, or antennæ wires, that are spread around the top and usually supported, in such position, by a definite frame-work rigidly fastened to the mast itself. Heretofore there has been no manner of thus affixing the frame-work to the mast, that has permitted the withdrawal of the same, and its attendant wires, from their normal place, without a total dismantling of all the parts involved. This operation, besides being costly and slow, must, necessarily, be undertaken under conditions that make the result uncertain and largely dependent, for any expedition, at least, on the particular circumstances or situation in each case.

It is the object of the invention I am now about to describe, to afford a form of support for the antennæ wires of an electric mast, that is adequate for that purpose and, at the same time, by reason of the mechanical principle of its construction, and without the need of dismembering the same, can readily be manipulated whenever it is desired to inspect, renew or repair such wires, or frame. To this end, as, set forth in the several figures, I show, as a primary element of the arrange-

ment, when comprehensively considered, an electrically insulated mast carrying and surrounded by a support for its antennæ-wires that can always be mechanically withdrawn, or extended, from the mast to the normal, as occasion requires, and without any special preliminary steps.

In the drawings accompanying, and intended to make clear my said invention, Figure 1 is an enlarged view of the top of a mast, equipped with my invention, when the antennæ wires, supported by the same, and the support itself, are withdrawn to the mast for inspection, repair etc. Fig. 2 is an enlarged view of the top of a mast carrying said support, Fig. 3 is a downward plan of the frame of said support with antennæ wires strung across the same, Fig. 4 is a plan view of a detail of a mode of connecting the sustaining wires to the outer extremities of the gaffs or booms employed as a part of said support, Fig. 5 is a side elevation of Fig. 4. Fig. 6 is an elevation of a portion of the mast, and of that part of said support that is in sliding engagement with the same, Fig. 7, is a plan view of the parts shown in Fig. 6. Fig. 8 is an enlarged sectional view of the shoe and guide detail shown in Fig. 7. Fig. 9 shows a mechanical arrangement fixed at the top of the mast for taking in or letting out, the sustaining wires when said support is withdrawn for inspection or is extended to its normal place. Fig. 10 is a down plan of Fig. 9. Fig. 11 is an elevation of a special form of the support where both horizontal and vertical antennæ are used, the front booms being removed. Fig. 12 is an elevation of another special form where the lower frame structure of the support is permanently fixed to the mast.

In the drawings M is the mast proper (which, as said, is a hollow cylindrical shaft provided with an interior ladder m) and G^1 , G^2 , and G^3 its sustaining guys. b^1 , b^2 , b^3 , b^4 and b^5 , indicate repair balconies on said mast.

O is a canopy at the mast top, and T represents an insulating hood over the guy terminals. Surrounding said mast, near its top, is a square frame-work whose sides are, each, made up of channels f and f' , fastened together, at their inner ends, by means of gusset plates p , p . Said frame-work is connected with a second and interior frame-

work, around the mast, by the struts s^1 and s^2 that extend, respectively, from the corners, and the middle points, of the outer frame-work, referred to, to gusset plates p' , that connect the several sides f^1 of said interior frame-work. As appears, each pair of struts, are made to converge, from their interior fastenings, toward their fastening to the gusset plate p , at said middle points of the outer frame-work, with their ends parallel to each other, at such point, so as to form a clevis-like bearing to which the booms B may be pivotally attached, as is to be explained. Said outer frame-work is, further connected to a second inner frame-work F , below, (like and similarly related to the mast as the first) by the several struts s^3 , thereby, forming, with the latter, a firm frame-structure with two horizontal bearings against the mast. At diametric points on the sides of said outer frame-work, between the clevis-bearings specified, are vertically pivoted booms or gaffs B to which the antennæ wires are to be strung. They are of such length that, when distended diagonally upward, the field or area between their ends, shall be ample for the purpose. They are stayed against lateral movement by guys, g^1 , on each side of the same, that are anchored to the corners of said structure, and the latter should be of suitable dimensions, in every case, to afford the requisite purchase for the purpose. Backstays t from the outer ends of the booms to a suitable distance on the mast below are also shown and on each side of said outer ends is a horizontal sheave and block V transversely pivoted thereto by pivots o . Sustaining ropes R are stretched between and from the ends of adjoining booms, when in their distended or normal positions, to which ropes antennæ wires N are attached and their free ends brought together in a knot (Fig. 3) and connected directly to the mast, when metallic, or to suitable conducting wires when the mast is a non-conductor. It will of course be seen, that, under these conditions, when the booms B , and sustaining ropes R , are in their normal positions the antennæ, arranged as just described, will lead or extend to the mast in a horizontal plane.

Between the inner edges of the plates p' and the mast M , are upright shoes S , S , consisting of an upright angle-bar or piece fastened to said plates with their legs toward the mast between the outwardly extending flanges of a vertical channel-beam C , that is riveted to the exterior surface of the mast for the purpose. The channel beams C should extend downwardly from the highest travel or point on the mast to be occupied by the boom-frame above described, to a distance from the top of the mast equal to the length of a boom and the distance between said outer and inner frame-works.

At a fixed point on the mast M immediately above said highest point on the same, is located a chain-hoist system, made up of two chain-hoist wheels H , H , at opposite sides of the mast, upon an axle a , (passing through the mast), and the hoist-chains c . One end of the hoist-chains c is fastened to said frame structure and, as indicated in Figs. 6 and 7, suitable means for operating said system, by a worm-gearing, for instance, actuated by the wheel h' and chain c' located within said mast.

At the top of the mast is an arrangement for taking in the sustaining ropes R , and their antennæ-wires, consisting of four diametrically related sets of two drums each D , D , at the exterior of the mast near the top. These several sets are arranged in pairs, revolute upon common shafts X , and are provided with ratchets r , at the end and integral with each drum. Pawls P and P' , are provided to be brought into gear with said ratchets to control the drums so they may be operated either simultaneously or separately, the former pawl being fixed on the frame-work of the drum and, the latter, pivoted to a socket T' , that engages the shaft X , of a hand-lever L , extending toward the center of the mast. Below the drums D is a framework w , inclosing and rigidly fastened to the mast that carries diametrically arranged sheaves v . Balance ropes l , are, preferably, attached to said booms, and brought around said sheaves downwardly to the framework to which the booms are affixed. The sustaining ropes R , are reaved around the sheaves V , at the end of and between each adjoining pair of booms B , and, thence, are brought to and around, from the under side of the drums D , in each case, and fastened to the same.

In the special application of my invention more particularly set forth in Fig. 2, it is manifest that, by the arrangement of the guys and ropes shown, the booms will be securely stayed and held in their normal or extended position, but that, by reason of the peculiar method of connecting them to the mast, they can readily be withdrawn to the mast, with the attached antennæ-wires, whenever it is desired to inspect, or repair either the wires, or any part of the supporting frame. All that will be necessary, in such case, will be that an operative take a position within the mast, and by means of the wheel h' and chain c' , unwind, or reversely turn the chain-hoist wheels H , and, thereby allow the frame-structure, to which the booms B , are pivoted, to descend by gravity down the channel-beam guides C , until the booms are drawn in and lie vertically near the mast to their full length, as shown in Fig. 4. During this process, a second operative will, in turn, have actuated the drums D carrying the sustaining ropes R , by means of

the hand-lever L, in engagement, through the pawls P', with the ratchets r, so as to take up the slack of the free portions of said ropes, as the booms approach the mast. In said operation both members of each pair of drums are worked in unison, but when it is only desired, for instance, to tighten up a particular sustaining rope, with its attached antennæ wires, it is plain that it will merely be necessary, to throw out of gear the pawl P, of the companion drum on the same shaft X, and the other drum member, controlling the rope to be tightened, can then be worked alone and independently of the other. It is evident, also, that, by allowing the frame-structure to which the booms are attached, to descend to the full length of the channel-guides C, as described, the antennæ wires can be taken in during the process, hand over hand, and examined, and repaired or replaced. In order to cause the booms and their wires to resume their normal places, it will only be necessary to reverse the directions just given for withdrawing them from such places.

Special forms for multiplying the wire-carrying capacity of a support, of the character I have described, are illustrated in Figs. 11 and 12. That shown in Fig. 11 differs from the previously shown form by the introduction, below the set of booms shown before, of a duplicate or secondary set of booms pivoted to a second-frame structure like the first, and, oscillating in upright guides, on the mast, C' C' for the purpose. Said latter set of booms, carry between their outer extremities, a sustaining rope R', to which are attached the lower ends of antennæ-wires N', which extend vertically from the upper sustaining rope R. The sustaining ropes R' are attached directly to the booms B', without the intervention of sheaves corresponding with V, and any drum arrangement for withdrawing the same to the mast, as in case of the upper set, is unnecessary, inasmuch as the lower frame, to which the booms B' are pivoted, is connected or tied directly to the upper oscillating frame to which the booms B are pivoted, by hangers E, so that whenever the upper frame is oscillated, the lower frame will thereby be carried up or let down, as the case may be. b⁴ is a repair balcony for the lower booms and wires, located at the point on the mast where the ends of the booms B' come in, where their frame is lowered to its full predetermined limit. l', l', are compensating stays to balance the stay l on the upper set of booms B; t', t', etc. are back-stays between said upper and lower booms and, t², t² back-stays from the outer ends of the booms B' to the mast. Each boom B' is stayed against lateral movement by the boom-guys g' extending from its top, on either side to anchorages on the frame-structure itself.

The special form just described is, of course, operated, so far as the crown-wires etc. at the upper set of booms are concerned, as already explained; in so doing it is manifest that, as the upper frame-structure descends along the mast, the lower frame-structure and its boom B' will equally descend, by gravity, and that the wires and all parts pertaining to the latter booms can be overhauled by an operative stationed on balcony b⁴.

Still another special form of support is shown in Fig. 12. In this form there is an upper arrangement of booms etc., like that shown in previous figures, and a lower frame-structure to which booms B² are pivoted, as in the form shown in Fig. 11. This lower frame-structure, however, is not arranged to oscillate upon the mast, but is permanently fixed at one point thereon, with back-stays t² from the ends of its upper booms B, anchored to the mast, rather than to the lower booms B². b⁵ is a balcony on the mast, at the point where the ends of the booms B² come in when folded up against or vertical with the mast. At said balcony are located drums, or other suitable mechanism (indicated by U) for winding in the ropes l² l² which extend from the ends of the booms B² and are fastened to said winding mechanism, and thereby serve both to sustain its booms in their extended or normal position and to haul them up and in. Boom-guys g, having the same functions as g² and g', are strung at either side of the several booms B², from their tops or ends to their supporting frame-structure. R², R² are sustaining ropes for a series of antennæ wires W² W², extending vertically between the same and the upper sustaining ropes R R and attached thereto. t³ t³ are back-stays from the ends of the booms to the mast beneath. Of course, in this case, in order to inspect or handle the wires W², and their allied parts, it will only be necessary to lower the frame-structure to which their booms are pivoted, by unfastening the back-stays t³ and then winding in the rope l² until the booms are brought upright on their pivots close to the mast. It is clear that unlike the arrangement shown in Fig. 14, the last described arrangement makes it entirely practicable to handle either set of booms independently of the other, or both at the same time.

I wish it to be understood, that I do not wish my invention, in the broader sense, to be confined to only those forms of construction where the several features described are present in the precise form displayed; in such sense the several methods of staying or guying the different parts, for instance, are not of the essence of the invention, nor the peculiar arrangement of the sheaves, drums, or frame-structures, or the exact number of the frame-structures shown and appendant

booms, the main or controlling idea, being the boom supports, vertically pivoted to an oscillating frame-structure or structures to and between which booms the antennæ are 5 flexibly strung.

What I claim and desire to secure by Letters Patent is—

1. A support for antennæ wires of electric masts, made up of an oscillating frame-structure upon said mast, booms vertically pivoted thereto and flexible supports for said wires, extending between and connected with the outer ends of said booms, substantially as shown and described.
- 15 2. In a support for antennæ wires of electric masts, the combination of an oscillating frame-structure upon said mast, booms vertically pivoted thereto, and flexible supports for said wires, extending between and connected with the outer ends of said booms, substantially as shown & described.
- 25 3. A support for antennæ wires of electric masts, comprising an oscillating frame-structure upon said mast, booms vertically pivoted thereto, flexible supports for said wires between and connected with the outer ends of said booms, and suitable guys and stays from said booms to said mast and frame-structure to maintain the same in a diagonal 30 position with respect to said mast, when said booms are lowered on their pivots for the purpose, substantially as shown and described.
- 35 4. A support for antennæ wires of electric masts, comprising an oscillating frame-structure upon said mast, booms vertically pivoted thereto, flexible supports for said wires between and connected with the outer ends of said booms and with suitable mechanism 40 for winding in the same, provided for the purpose, and suitable guys and stays from said booms to said mast, and frame-structure

ture to maintain the same in a position diagonally outward with respect to said mast, when lowered on their pivots for the purpose, 45 substantially as shown and described.

5. In combination with an electric mast, a support for antennæ wires, comprising an oscillating frame-structure surrounding said mast, booms vertically pivoted to the sides 50 thereof, flexible supports for said wires between and connected to the outer ends of said booms, and extending backwardly and fastened to suitable mechanism, provided for the purpose at the mast, for winding in the 55 same, and suitable guys and stays, from said mast and frame-structure to said booms, to maintain the same in a diagonal position with respect to the mast when lowered outwardly on their pivots for the purpose, all 60 substantially as shown and described.

6. In combination with an electric mast, a support for antennæ wires, comprising an upper and lower oscillating frame-structure surrounding said mast, radial booms vertically 65 pivoted to the same, flexible supports for said wires between and connected to the outer ends of the said booms of each structure, and, in the uppermost of said set of booms, extending backwardly and fastened 70 to suitable mechanism at the mast for winding in the same, hanger-like connections between said structures, suitable guys and stays between said sets of booms, and between said booms and said mast, and frame-structure, 75 to maintain said booms, in a diagonal relation to said mast when lowered outwardly on their pivots for the purpose, substantially as shown and described.

ALEXANDER E. BROWN.

In presence of—

A. M. MERRYWEATHER,
R. B. SHERIDAN.
